CARBURETORS, INCLUDING AN AUXILIARY STARTING DEVICE

André Louis Mennesson, Neuilly-sur-Seine, France, assignor to Solex S. A., Neuilly-sur-Seine, France, a society of France

Application September 10, 1954, Serial No. 455,274

Claims priority, application France September 25, 1953

9 Claims. (Cl. 261—41)

The present invention relates to carburetors including an auxiliary starting device capable of delivering fuel toward the engine under the effect of the suction existing in the induction pipe thereof downstream of the carburetor throttle, said auxiliary device comprising an independently operated distributing valve for controlling the delivery of fuel toward the downstream side of the throttle and means operative by said distributing valve for slightly displacing said throttle in the opening direction from its maximum closing position when said distributing valve is moved into a position in which it delivers fuel toward the downstream side of the throttle, whereby at least a portion of the air to be mixed with the fuel supplied through said distributing valve is admitted through the passage thus afforded by said throttle.

The object of the present invention is to improve the operation of such carburetors, whether their distributing valve is operated manually or automatically.

They consist chiefly in providing such carburetors with means such that the section of flow afforded to the fuel flowing from the auxiliary starting device toward the engine induction pipe, downstream of the throttle, is controlled under the effect of the suction existing at this place in said pipe, so as to be reduced when said suction exceeds a predetermined value.

Preferred embodiments of my invention will be hereinafter described with reference to the accompanying drawings, given merely by way of example, and in which:

Fig. 1 diagrammatically shows, partly in elevational view and partly in sectional view, a carburetor made according to my invention.

Fig. 1a is a partial view showing a modification.

Fig. 2 is a partial section on the line II—II of Fig. 1.

Fig. 3 shows, similarly to Fig. 1, but in a different relative position of the parts, a portion of said carburetor.

Figs. 4 and 5 are views similar to Fig. 1 but corresponding to two different relative positions of the parts, these views showing the distributing valve of the carburetor.

On Fig. 1, reference character 1 designates the body of the carburetor, 2 the induction pipe and 5 the throttle. The carburetor includes a constant level chamber 6 which feeds fuel to the auxiliary starting device through a jet 12. The auxiliary starting device includes a well 11 opening to the atmosphere at its upper part through a calibrated passage, an upward conduit 13 extending in said well, and a downward conduit 14. In the embodiment of Fig. 1, the upward conduit consists of a tube provided with holes disposed both in the end thereof and laterally. As in the embodiments above described, this tube is connected at its upper part with downward conduit 14.

Now, according to the present embodiment, the carburetor is provided with means such that the cross section afforded to the stream of mixture flowing from the auxiliary starting carburetor toward the induction pipe of the engine downstream of the throttle is controlled in response to variations of the suction existing in

2

said pipe at this place in such manner as to be reduced when said suction exceeds a predetermined value.

Furthermore, preferably, supplementary means which may be combined with those just above mentioned are provided so that the suction exerted on the fuel supplied by the auxiliary starting carburetor is reduced when the suction existing in the induction pipe, downstream of the throttle, exceeds a predetermined value, which may be the same as that just above mentioned.

10 In the embodiment of Fig. 1, the distributing valve is constituted by a disc of substantially cylindrical shape 43, pivotally mounted about an axis 44 and kept by a spring 45 in fluidtight contact with a flat surface provided on the body of the carburetor.

This disc 43 is provided with a central recess and with three radial grooves 46 preferably at 120° to each other, as shown in dotted lines on Figs. 1, 4 and 5.

An operating lever 47 is fixed to disc 43 which also carries a cam 20. This cam is adapted to cooperate, as above indicated, with a lever 23 freely rotatable on the spindle of throttle 5 and including an abutment 25 upon which bears an adjustable screw 26 carried by a lever 18 fixed on the spindle of throttle 5 and connected with the throttle spindle.

25 Three conduits or channels open into the flat surface which cooperates with disc 43.

The first one is the above mentioned downward conduit 14, the opening of said conduit into said surface communicating, through a calibrated passage 48 (Fig. 4) with a small recess 49 which will be hereinafter more explicitly referred to.

30 The second of these conduits, designated by reference numeral 50, communicates with a cylindrical chamber 51, which will also be more explicitly referred to hereinafter.

The third of said conduits, designated by reference character 52, communicates also with said chamber 51 as it will be hereinafter explained.

35 Chamber 51 is formed, preferably vertically, in the body 1 of the carburetor. Its upper end communicates through a passage 53 with the main air intake of the carburetor and its lower end communicates with the engine induction pipe, downstream of the throttle, through a conduit 54, which extends upwardly in said chamber 51 in the form of a tube 55 provided at its upper end with a large area aperture 56 and, its side wall, with a passage 57 of substantially smaller area.

40 A piston 58 is slideable in chamber 51 above tube 55, and this piston is urged upwardly by a spring 59 of suitable characteristics as will be explained hereinafter.

The whole is arranged in such manner that when said piston 58 is in its lowermost position, as shown by Fig. 3, it closes the large area passage 56 provided at the top of tube 55 while it opens the outlet of conduit 52 into chamber 51 thus causing this outlet to communicate through passage 53 with the main air intake of the carburetor.

On the other hand, when piston 58 is pushed upwardly 45 by spring 59 (Fig. 1) so as to be brought into contact with its abutment 60, said piston stops the outlet of conduit 52 and simultaneously opens the large area passage 56 of tube 55, thus connecting it with conduit 50.

50 Conduits 14, 50 and 52 open into the flat surface of the carburetor body, which cooperates with disc 43, in such manner that each of these channels can either be stopped by disc 43 or on the contrary be placed in communication with one of the three radial grooves 46 provided in disc 43, according to the position of said disc.

55 For instance, in Fig. 1, disc 43 is in a position such that the three conduits 14, 50 and 52 communicate freely to

3

gether through grooves 46 and the central recess of disc 43.

On the contrary, in Fig. 4, where disc 43 is shown as having been slightly rotated in the clockwise direction, conduit 14 is in communication with the corresponding radial groove of disc 43 only through the small area recess 49, whereas the communication between conduits 50 and 52 takes place only through a passage of smaller section.

Finally, in Fig. 5, the three conduits above referred to 10 are fully separated from each other.

Of course, the openings of conduits 14, 50 and 52 into the flat surface of the carburetor body and/or the grooves of disc 43 are provided in such manner that, starting from the fully open position of the distributing valve 15 (starting from cold), as shown by Fig. 1, when said distributing valve is gradually closed the flow of sections supplied by the distributing valve for the three above mentioned channels also decrease gradually until they are fully stopped.

Cam 20 is arranged in such manner that when the distributing valve is in the fully opened position (Fig. 1), throttle 5 is slightly opened whereas when the distributing valve is being gradually closed, the throttle is also gradually returned (Fig. 4) to its idling running position 25 (Fig. 5).

This device works in the following manner:

It is known that when the engine has to be started from cold it is necessary to obtain a very rich mixture whereas on the contrary this mixture must very quickly become 30 leaner as soon as the engine has been started.

On the other hand, when the engine is running but before it has reached its normal temperature of operation, it is necessary to obtain, for all running conditions, a mixture which is slightly richer than that normally supplied 35 by the normal jet systems of the carburetor.

These conditions can be complied with owing to the provision of piston 58 and of the distributing valve constituted by disc 43.

When starting from cold, the elements are in the relative positions shown by Fig. 1. Lever 47 then causes the displacement of lever 23 by cam 20 to be maximum. This lever 23, which acts through its abutment 25 on screw 26, actuates lever 18 and throttle 5 to open it to a degree slightly greater than the normal opening for idling running.

The three radial grooves 46 connect together conduits 14, 50 and 52. Piston 58, which is pushed upwardly by a spring, affords a free passage through tube 55 toward conduit 54.

When the engine is driven by the starter, there is produced in the induction pipe a suction the value of which determines the strength to be given to spring 59. This spring must be sufficiently strong to keep piston 58 in upper position despite the action of said suction thereof.

In these conditions, this suction, which is relatively low because of the small speed with which the engine is driven by the starter, sucks in fuel from well 11 through the orifices of tube 13 and through conduits 14, 50 and 54.

As no air inflow is provided to weaken the suction exerted on the fuel in tube 13, I obtain a mixture as rich as it may be desired and the richness of which is determined by the choice of jet 12, of the calibrated air passage provided at the top of well 11 and of the orifices provided in tube 13.

As soon as the engine is running, its speed suddenly increases from 100/150 revolutions per minute to at least 700/800 revolutions, and consequently the suction in the induction pipe and in conduit 54 becomes much higher than when the engine was being driven by the starter.

The characteristics of spring 59 must be such that, in these conditions, piston 58 is then moved down by the suction existing in conduit 54 and closes the large area passage 56 provided at the top of tube 55, allowing 75

4

fuel to pass only through calibrated hole 57 (Fig. 3). Simultaneously, the opening of conduit 52 is cleared and air penetrates, under the effect of the suction, through conduit 53, conduit 52 and the radial grooves 46 of the distributing valve, this air being directed toward conduit 50. The suction which is exerted on the fuel in tube 13 is therefore considerably lowered.

Thus, whereas the section of the air passage supplied by the opening of throttle 5 remains unchanged, the section through which fuel is allowed to pass and the suction exerted on this fuel are considerably reduced. I thus obtain, as soon as the engine is running by itself, a considerable reduction of the richness of the mixtures, whereby it is possible to make use of extremely rich mixtures when the engine is being driven by the starter, while obtaining normal mixtures as soon as the engine has been started and is running by itself.

As the engine is warming up, the driver is led to reduce the action of the auxiliary starting carburetor, chiefly in 20 order to reduce the speed of the engine. This action is exerted either manually or automatically according as the construction of the apparatus may be, but the principle remains the same in both cases.

For instance, Fig. 4 shows an intermediate position of disc 43 between the maximum acting position (Fig. 1) and the disconnecting position (Fig. 5). This Fig. 4 shows the three radial grooves of disc 43 connecting together only small sections of conduits 14, 50 and 52. It follows that the section of the passage of fuel is reduced while cam 20 enables lever 23 to move in anti-clockwise direction, which gradually returns throttle 5 into a position closer to idling running position.

Thus, by moving lever 47 in the clockwise direction, I obtain a reduction of the air flow section, and at the same time a reduction of the fuel flow section, which contributes in reducing the speed of the engine.

Fig. 5 shows the disconnecting position for which none of the three conduits 14, 50 and 52 is in communication, whereas lever 23 is no longer in contact with cam 20 and occupies a fixed position corresponding to the idling running position of the throttle.

The system above described further has the following advantageous feature.

It is known that as long as disc 43 has not reached the 45 disconnecting position thereof, when throttle 5 is opened by the throttle pedal acting upon lever 18, the suction exerted in conduit 54 drops whereas, on the contrary, the main jet system starts feeding fuel into the carburetor.

The supplementary amount normally supplied by conduit 54 is no longer sufficient, due to the reduction of the suction, to give the total mixture supplied by the carburetor a sufficient richness and it is necessary, at this time, to have the amount of fuel supplied by conduit 54 substantially increased.

This is what is obtained owing to the provision of piston 58 which, being no longer subjected to the action of a high suction, is returned by spring 59 against its abutment 60, thus clearing conduit 50 and stopping conduit 52.

In these conditions, the amount of fuel that passes 60 through conduit 54 increases substantially and enriches the total mixture supplied by the carburetor.

I thus obtain, as long as the distributing valve is in operation, and for all running conditions, an increase of the richness of the mixture which is necessary for a good operation of said engine.

Fig. 1a shows a modified construction of the portion of the carburetor including piston 58 and the parts which cooperate therewith.

In the modified construction of Fig. 1a, tube 55 is dispensed with. Piston 58 has its open end turned downwardly instead of upwardly as in Fig. 1. The outer wall of this piston is provided with an annular groove in the bottom of which is provided a small hole 57a extending through the piston hole.

With this arrangement, when piston 58 is held in upper

position by spring 59 fuel can flow directly from conduit 59 into conduit 54 (which corresponds to fuel flowing through the large area opening 56 of tube 55 in the construction of Fig. 1). On the contrary, when the suction increases in conduit 54, piston 58 moves down and this direct large area passage is replaced by hole 57a (corresponding to hole 57 of Fig. 1). The operation is therefore equivalent.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In a carburetor including an induction pipe and a throttle in said induction pipe, an auxiliary starting device which comprises, in combination, a conduit opening into said induction pipe downstream of said throttle, a source of fuel, a conduit leading from said source, a distributing valve for controlling the flow of fuel from said source to said induction pipe, said valve being provided with a passage arranged to interconnect said two conduits for a given position of said valve, means operatively connecting said distributing valve with said throttle for opening said throttle from its maximum closing position in response to the bringing of said valve into said position, and means, responsive to variations of the suction in said induction pipe downstream of said throttle, for throttling one of said conduits for increases of said suction above a predetermined value.

2. In a carburetor including an induction pipe and a throttle in said induction pipe, an auxiliary starting device which comprises, in combination, a conduit opening into said induction pipe downstream of said throttle, a source of fuel, a conduit leading from said source, a distributing valve for controlling the flow of fuel from said source to said induction pipe, said valve being provided with a passage arranged to interconnect said two conduits for a given position of said valve, means operatively connecting said distributing valve with said throttle for opening said throttle from its maximum closing position in response to the bringing of said valve into said position, and means, responsive to variations of the suction in said induction pipe downstream of said throttle, for throttling said first mentioned conduit for increases of said suction above a predetermined value.

3. In a carburetor including an induction pipe and a throttle in said induction pipe, an auxiliary starting device which comprises, in combination, a conduit opening into said induction pipe downstream of said throttle, a source of fuel, a conduit leading from said source, a distributing valve for controlling the flow of fuel from said source to said induction pipe, said valve being provided with a passage arranged to interconnect said two conduits for a given position of said valve, means operatively connecting said distributing valve with said throttle for opening said throttle from its maximum closing position in response to the bringing of said valve into said position, and a single means, responsive to variations of the suction of said induction pipe downstream of said throttle, for throttling said first mentioned conduit for increases of said suction above a predetermined value, and for reducing the total suction exerted on the stream of fuel controlled by said distributing valve for increases of said first mentioned suction above said predetermined value.

4. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said

housing and opening into said induction pipe downstream of said throttle, two passages in said carburetor body opening into the cylindrical wall of said housing, one near the first mentioned end thereof the other near the second mentioned end, a distributing valve for controlling the flow of fuel from said source to said induction pipe, said valve being arranged to connect, for a given position thereof, both said first mentioned conduit and said first mentioned passage with said second mentioned passage, and slide valve means in said housing movable in response to suction variations in said second mentioned conduit for connecting said second mentioned passage with said second mentioned conduit through a large area section of flow while closing said first mentioned passage when said suction is low and connecting said second mentioned passage with said second mentioned conduit through a small area section of flow while opening said first mentioned passage when said suction is above a given value.

5. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said housing and opening into said induction pipe downstream of said throttle, two passages in said carburetor body opening into the cylindrical wall of said housing, one near the first mentioned end thereof the other near the second mentioned end, a distributing valve for controlling the flow of fuel from said source to said induction pipe, said valve being arranged to connect, for a given position thereof, both said first mentioned conduit and said first mentioned passage with said second mentioned passage, means operatively connecting said distributing valve with said throttle for opening said throttle slightly from its maximum closing position in response to the bringing of said valve into said position, and slide valve means in said housing movable in response to suction variations in said second mentioned conduit for connecting said second mentioned passage with said second mentioned conduit through a large area section of flow while closing said first mentioned passage when said suction is low and connecting said second mentioned passage with said second mentioned conduit through a small area section of flow while opening said first mentioned passage when said suction is above a given value.

6. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said housing and opening into said induction pipe downstream of said throttle, two passages in said carburetor body opening into the cylindrical wall of said housing, one near the first mentioned end thereof the other near the second mentioned end, a distributing valve for controlling the flow of fuel from said source to said induction pipe, said valve being arranged to connect, for a given position thereof, both said first mentioned conduit and said first mentioned passage with said second mentioned passage, a tube forming an extension of said second mentioned conduit into said housing, said tube having its end located in said housing open and being provided in its side wall located in said housing with a hole of a section smaller than that of said open end, a piston slidable in said housing in the portion thereof beyond said tube, said piston having one end adapted to fit on said tube open end so as to stop it, said piston being adapted, when in the position where said end thereof is closing said tube open end, to uncover the opening of said first mentioned passage into said hole, and, when it is moved away from said position, to cover said opening, and spring means be-

7
tween said piston and the second mentioned end of said casing for urging said piston away from said housing second mentioned end, said spring means being adjusted to oppose the effect of a low suction in said second mentioned conduit and to yield to a higher suction.

7. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said housing and opening into said induction pipe downstream of said throttle, two passages in said carburetor body opening into the cylindrical wall of said housing, one near the first mentioned end thereof the other near the second mentioned end, a distributing valve for controlling the flow of fuel from said source to said induction pipe, said valve being arranged to connect, for a given position thereof, both said first mentioned conduit and said first mentioned passage with said second mentioned passage, means operatively connecting said distributing valve with said throttle for opening said throttle slightly from its maximum closing position in response to the bringing of said valve into said position, a tube forming an extension of said second mentioned conduit into said housing, said tube having its end located in said housing open and being provided in its side wall located in said housing with a hole of a section smaller than that of said open end, a piston slidable in said housing in the portion thereof beyond said tube, said piston having one end adapted to fit on said tube open end so as to stop it, said piston being adapted, when in the position where said end thereof is closing said tube open end, to uncover the opening of said first mentioned passage into said hole, and, when it is moved away from said position, to cover said opening, and spring means between said piston and the second mentioned end of said casing for urging said piston away from said housing second mentioned end, said spring means being adjusted to oppose the effect of a low suction in said second mentioned conduit and to yield to a higher suction.

8. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said housing and opening into said induction pipe downstream of said throttle, two passages in said carburetor body opening into the cylindrical wall of said housing, one near the first mentioned end thereof the other near the second mentioned end, a distributing valve for controlling the flow of fuel from said source to said induction pipe, said valve being arranged to connect, for a given position thereof, both said first mentioned conduit and said first mentioned passage with said second mentioned passage, a piston slidable in said housing, the end of said piston nearer to the second mentioned end of said housing

5
being open, and the opposite end being closed, the cylindrical wall of said piston being provided with a small hole adapted to register with said second mentioned passage when said piston is in its end position toward said second mentioned end of said casing, the length of said piston being such that it then uncovers said first mentioned passage whereas it covers it when said piston is moved away from the second mentioned end of said housing, and spring means between said piston and the second mentioned end of said casing for urging said piston away from said housing second mentioned end, said spring means being adjusted to oppose the effect of a low suction in said second mentioned conduit and to yield to a higher suction.

9. In a carburetor including a carburetor body provided with an air intake, an induction pipe and a throttle in said induction pipe, an auxiliary carburetor which comprises, in combination, a source of fuel, a conduit leading from said source, a cylindrical housing formed in said carburetor body and communicating at one end with said air intake, a conduit starting from the other end of said housing and opening into said induction pipe downstream of said throttle, two passages in said carburetor body opening into the cylindrical wall of said housing, one 15 near the first mentioned end thereof the other near the second mentioned end, a distributing valve for controlling the flow of fuel from said source to said induction pipe, said valve being arranged to connect, for a given position thereof, both said first mentioned conduit and said first 20 mentioned passage with said second mentioned passage, means operatively connecting said distributing valve with said throttle for opening said throttle slightly from its maximum closing position in response to the bringing of said valve into said position, a piston slidable in said housing, the end of said piston nearer to the second mentioned end of said housing being open, and the opposite end being closed, the cylindrical wall of said piston being provided with a small hole adapted to register with said second mentioned passage when said piston is in its end 25 position toward said second mentioned end of said casing, the length of said piston being such that it then uncovers said first mentioned passage whereas it covers it when said piston is moved away from the second mentioned end of said housing, and spring means between said piston and the second mentioned end of said casing for urging said piston away from said housing second mentioned end, said spring means being adjusted to oppose the effect of a low suction in said second mentioned conduit and to yield to a higher suction.
